ABSTRACT OF THE DISCLOSURE

A radio construction wherein the chassis, loudspeaker and clock are secured within the radio cabinet by integral guide members and flexible latching members to completely eliminate the necessity for conventional fastening devices.

This invention relates to constructions for radios and the like, and particularly relates to an arrangement for assembling a chassis, loudspeaker, clock, or the like, into a cabinet.

The main component parts of a radio, or like devices such as television sets, tape recorders, phonographs, etc., are usually assembled into a cabinet by means of screws or other fastening devices. Attempts have been made to reduce the use of such fasteners in order to reduce the cost of providing and installing them; however, a certain number of fasteners has been found necessary to insure adequate and secure attachment of the various parts to the cabinet. An attempt has been made to substantially eliminate the use of such fasteners by an arrangement wherein one part is arranged to support another part. For example, in such an arrangement the chassis holds the loudspeaker in place in the cabinet, and the removable back of the cabinet holds the chassis in place. Such an arrangement however, suffers the drawback that if one of the latter parts should become loose, the rest of the parts can become loose or fall out of the cabinet.

An object of the invention is to provide an improved construction for radios and the like.

Another object is to provide a low-cost construction for radio and the like.

A further object is to provide a construction for radios and the like, which eliminates the use of conventional fastening devices.

Still another object is to provide an improved construction for radios and the like, in which the component parts are securely attached to the cabinet without the use of conventional fastening devices.

Additional objects will be apparent from the following description and claims, and from the accompanying drawing.

The invention comprises, briefly and in a preferred embodiment, a cabinet into which at least one component part is to be held in place, guide members in the cabinet for positioning the part in two dimensions, and a flexible latch member integral with the cabinet and arranged to resiliently engage against the component part in locking engagement therewith to secure the part in the third dimension, whereby the part is held to the cabinet in all three dimensions.

Various ways of carrying out the invention will be described in detail.

In the drawing:

FIG. 1 is a front view of a radio constructed in accordance with a preferred embodiment of the invention,

FIG. 2 is a rear view of the radio of FIG. 1, with the back of the radio partly broken away to reveal interior construction,

FIG. 3 is a cross-sectional view of a portion of the radio, taken at the line 3—3 in FIG. 2,

2

FIG. 4 is a cross-sectional view of a portion of the radio, taken at the lines 4—4 in FIG. 2,

FIG. 5 is a view similar to that of FIG. 4, but with a component part of the radio partially removed from place, in order to illustrate the functioning of the invention,

FIG. 6 is a cross-sectional view of a portion of the radio, taken at the line 6—6 of FIG. 2,

FIG. 7 is a cross-sectional view of a portion of the radio, taken at the line 7—7 of FIG. 2,

FIG. 8 is a cross-sectional view of a portion of the radio, taken at the line 8—8 of FIG. 2,

FIG. 9 is a cross-sectional view of a portion of the radio, taken at the line 9—9 of FIG. 2,

FIG. 10 is a cross-sectional view of a portion of the radio, taken at the line 10—10 of FIG. 2, and

FIG. 11 is a cross-sectional view of a portion of the radio, taken at the line 11—11 of FIG. 2.

Now referring primarily to FIGS. 1, 2 and 3 of the drawing, the radio as illustrated comprises a cabinet 11 preferably made from a plastic material that is somewhat resilient. At the front of the cabinet 11 is a tuning dial 12 which actuates a tuning capacitor 13, a volume control knob 14 which actuates a volume control device 16, and a dial 17 of a clock mechanism 18.

Three major component parts of the radio—a printed circuit board chassis 21, a loudspeaker 22, and the clock 18—are attached to and held by the cabinet 11 in accordance with the invention.

The printed circuit board chassis 21, which may carry tubes 22, the tuning capacitor 13, and other components, in well-known manner, is accommodated in the cabinet 11 by means of a pair of mutually parallel guide slots or grooves 26 and 27 formed in ribs 28 and 29 which preferably are an integral part of the molded cabinet 11.

The parallel guide grooves 26 and 27 are arranged so that the circuit board 21 can slide therein from the rear of the cabinet 11, whereby opposite edges of the board 21 lie in the grooves 26 and 27, whereby the chassis 21 is held in two dimensions, i.e., in the dimension perpendicular to the plane of the chassis board 21 and also in the dimension across the board 21 from one guide groove 26 to the other guide groove 27. If desired, slotted ribs may be provided inside the cabinet 11 near the front thereof to act as a forward stop for the circuit board 21 and also to give it additional support, as indicated by the slotted rib members 31 and 32 in FIG. 3. As shown in FIG. 3, the guide rib 29 is composed of two aligned portions, 29a and 29b. Between the rib portion 29a and 29b, a latch member 36 is molded integrally with the cabinet 11, the latch member 36 preferably being provided by a U-shaped slot as shown in FIG. 3. The latch member 38 is attached to the cabinet 11 at the rear end 37 of the latch member 36, the other end of the latch member 36 comprising a laterally projecting portion which tapers substantially to a point 38 arranged to fit into a notch 39 in the edge 41 of the circuit board 21 which is located in the guide slot 27.

The latch member 36 is arranged to be resiliently movable substantially in the plane coincident with that of the circuit board 21. Thus, when the circuit board or chassis 21 is placed in the guide grooves 26 and 27 and pushed forwardly, the edge 41 of the board 21 will deflect the latch member 36, as shown in FIG. 5. The latter is readily achieved, due to the tapered rear surface 42 of the latch member 36, whereby the edge 41 of the circuit board 21 readily deflects the latch member to the position shown in FIG. 5 until the circuit board 21 is in place, whereupon the tip 38 of the latch member 36 resiliently engages into the slot 39 so as to hold the chassis board 21 in its remaining or third dimension, whereupon the chassis board 21 now is securely retained to the cabi-

60
65
70

net 11 in all three dimensions. The front edge 43 of the latch member 36 is slightly tapered so as to wedge against the leading edge 44 of the slot 39 to prevent any "play" of the chassis board with respect to the cabinet 11. The slot edge 44 may also be tapered, as shown, so as to cooperate in the wedging relationship with the front edge 43 of the latch member 36.

If it should be desired to remove the chassis board 21 from the cabinet 11, the latch member 36 is manually deflected to the position shown in FIG. 5, and the chassis board 21 is then slid rearwardly out of the guide slots 26 and 27. The latch member 36 is readily deflected to the position shown in FIG. 5, either by pressing it downwardly with the fingers from inside the cabinet 11, or by inserting a screwdriver blade or similar object in the space between the edge 43 of the latch member 36 and the adjacent edge 46 of the cabinet and then prying the latch member 36 downward to the position shown in FIG. 5.

The latch member 36 preferably is provided at the bottom of the cabinet 11, as shown, so as to be out of sight in normal use of the radio, and yet to be readily available for deflecting into the position shown in FIG. 5 for removal of the chassis board 21. The latch member 36 may be arranged to be deflected in a direction lying in the plane of the chassis board 21, or in a plane perpendicular thereto, or in some intermediate direction, so long as the tip portion 38 thereof is arranged to engage into the slot 39 in order to secure the chassis board 21 as has been described.

The loudspeaker 22 is attached to the cabinet 11 as follows, in accordance with the invention. A pair of notched ribs 51 and 52, which are molded integrally with the cabinet 11, are arranged for the upper edge of the loudspeaker 22 to fit in the notches thereof, as shown in detail in FIG. 6, whereupon the lower portion of the loudspeaker 22 is pushed forwardly whereby one or more openings 53 in the frame of the loudspeaker 22 fit over projections 54 that are molded integrally with the cabinet 11, as shown in detail in FIG. 10. As the lower portion of the loudspeaker 22 is pushed toward the front of the cabinet 11 as thus described, the lower edge 56 of the loudspeaker 22 deflects downwardly a pair of latching members 57, 58. With respect to the latch member 58, the latch members are molded integrally with the cabinet 11 and attached thereto at an end 59 thereof, so the head end 61 of the latch member 58 can be deflected downwardly. The upper portion of the head 61 of the latch member 58 is beveled, as clearly shown in FIG. 8 at numeral 62, so that as the lower portion 56 of the loudspeaker 22 is pushed forwardly in the direction of arrow 63, it will slide across the beveled surface 62 and deflect the head 61 of the latch member 58 downwardly in the direction indicated by the arrow 64. When the loudspeaker 22 is in the desired position as shown in FIG. 6, the head end 61 of latch member 58 will spring upwardly to the position shown in FIG. 8, so as to partially overlap the loudspeaker 22 at the rear surface thereof, thereby completing the holding in place of the loudspeaker 22 in the third dimension, the loudspeaker being held in other dimensions by means of the ribs 51 and 52, and the posts 54 extending through the opening 53 of the loudspeaker 22. The other latch member 57 functions similarly to the latch member 58 as has been described. The engagement faces 65 of the latch member 57, 58 may be beveled, if desired, so as to wedge tightly against the loudspeaker when in the position shown in FIG. 8. The loudspeaker may be additionally held in place, if desired, by means of a curved rib 71 extending rearwardly from the front of the cabinet 11 and shaped to conform to a curved corner of the frame of the loudspeaker 22, as shown in FIG. 9. A further positioning rib 72 may be provided, if desired, extending rearwardly from the front of the cabinet 11 adjacent an edge of the loudspeaker 22, as shown in FIG. 7.

The above-described construction for attaching the loudspeaker 22 to the cabinet 11, achieves quick assembly, by placing the upper edge of the loudspeaker 22 under the ribs 51 and 52, then pressing the lower portion of the loudspeaker towards the front of the cabinet 11, whereupon the latch members 57 and 58, being resilient, deflect until the loudspeaker is against the front of the cabinet, whereupon the latch members 57 and 58 automatically swing upwardly and in engagement against the rear of the loudspeaker 22 at the bottom thereof, thereby holding it securely in place in the cabinet 11. To remove the loudspeaker, the latch members 57 and 58 are pushed downwardly with the fingers, so as to release the lower edge of the loudspeaker 22 and permit it to be removed from the cabinet 11.

The clock 18 is attached to the cabinet 11 in a manner similar to that described above for the loudspeaker 22. The base plate 78 of the clock 18 has the upper edge thereof inserted upwardly into slotted rib members 76, 77 molded integrally with the cabinet 11, and the lower edge of the clock base plate 78 is then pushed forwardly towards the front of the cabinet 11, whereupon edges of the base plate 78 deflect and pass over latch members 79 and 80, which are molded integrally with the cabinet 11, whereupon these latch members assume the position shown in FIG. 2, tightly behind the base plate 78 so as to hold the clock 18 in place in the cabinet 11. The clock 18 may be readily removed from the cabinet 11, by deflecting the latch members 79 and 80 with the fingers so as to release the clock 18 and permit its removal from the cabinet.

From the foregoing, it will be seen that the objects of the invention have been achieved, whereby the component parts are assembled into a cabinet quickly and securely without the use of conventional fastening devices, thus saving not only the cost of fastening devices but also saving the cost of labor for attaching them. These objects are achieved at substantially no extra cost, due to the provision of the rib members and resilient movable latch members which are molded integrally as part of the plastic cabinet 11.

While preferred embodiments of the invention have been shown and described, various other embodiments and modifications thereof will be apparent to those skilled in the art, and will fall within the scope of invention.

What we claim is:

1. A construction for radios and the like in which a component part is to be attached to a cabinet, comprising positioning means located in said cabinet for positioning said parts in two dimensions when the part is placed in a desired position in the cabinet, and a resilient latch member integral at one end thereof with said cabinet and the other end thereof providing a resiliently movable portion having a transversely extending latch portion thereon positioned in the path of said component part when being placed in said desired position and adapted to engage against and hold said component part in a third dimension, said transverse latch portion being provided with a tapered surface adapted to be engaged by said component part for causing deflection of said latch member when the component part is being placed in desired position, whereby the transverse latch portion resiliently moves to holding engagement with the component part when in desired position.

2. A construction as claimed in claim 1, in which said transversely extending latch portion of said latch member which engages against said component part is beveled to provide a wedging engagement of the latch member against the component part.

3. A construction as claimed in claim 1, in which said latch member is provided in a wall of said cabinet by means of a U-shaped slot through said cabinet wall.

4. A construction for radios and the like in which a component part having a pair of opposite edges is to be

attached to a cabinet, comprising means defining a pair of spaced apart grooves in the interior of said cabinet adapted to receive said edges of the component part when said component part is in desired position in the cabinet, a resilient latch member integral at one end with said cabinet and the other end thereof providing a resiliently movable portion having a transversely extending latch portion thereon in juxtaposition with a portion of one of said edges of the component part when in desired position, said latch portion being movable laterally with respect to said one edge, and a notch in said one edge in alignment with said latch portion when the component part is in desired position, whereby said latch portion engages said slot and holds said component part in place in said grooves in said cabinet.

5. A construction as claimed in claim 4, in which said latch portion is provided with a tapered surface in alignment with said one edge of the component part for causing deflection of said latch member when said component part is being inserted in said grooves.

6. A construction as claimed in claim 4, in which at least one of said latch portion and said notch is provided with a beveled edge to provide a wedging action of said latch member against said component part.

7. A construction for radios and the like in which a component part having a pair of opposite edges is to be attached to a cabinet, comprising means defining a notched rib under which one of said edges can be placed for partially holding said component part in position whereupon the remaining edge of the component part is moved laterally into position in said cabinet, and a resilient latch member integral at one end thereof with said cabinet

5

10

15

25

30

and the other end thereof providing a resiliently movable portion having a transversely extending latch portion thereon positioned to overlie a portion of said component part at said remaining edge thereof so as to hold the component part in position in said cabinet.

8. A construction as claimed in claim 7, in which said movable latch portion is provided with a tapered surface in alignment with the path of said remaining edge of the component part when being moved into position, thereby causing deflection of the latch member when the component part is being placed in position.

9. A construction as claimed in claim 7, in which at least one of said latch portion and said component part is provided with a beveled surface to provide a wedging action of said latch member against said component part.
